US00D926823S

(12) **United States Design Patent** (10) Patent No.: **US D926,823 S**
(45) Date of Patent: **** Aug. 3, 2021**

(54) **DOOR OF A COMPACTOR**

- (71) Applicant: **Caterpillar Paving Products Inc.**,
Brooklyn Park, MN (US)
- (72) Inventors: **Michael S. Hemry**, Maple Grove, MN
(US); **Michael W. Ries**, Andover, MN
(US); **Paco Romero**, Brooklyn Park,
MN (US)
- (73) Assignee: **Caterpillar Paving Products Inc.**,
Brooklyn Park, MN (US)
- (**) Term: **15 Years**
- (21) Appl. No.: **29/738,557**
- (22) Filed: **Jun. 18, 2020**

Primary Examiner — Mark A Goodwin*(74) Attorney, Agent, or Firm* — Finnegan, Henderson,
Farabow, Garrett & Dunner, LLP.**CLAIM**The ornamental design for a door of a compactor, as shown
and described.**DESCRIPTION**FIG. 1 is a front, top, left perspective view of a door of a
compactor showing the new design;

FIG. 2 is rear, top, right perspective view thereof;

FIG. 3 is front elevation view thereof;

FIG. 4 is rear elevation view thereof;

FIG. 5 is left side elevation view thereof;

FIG. 6 is right side view thereof;

FIG. 7 is top plan view thereof; and,

FIG. 8 is bottom plan view thereof.

The claimed design includes the mirror image of the designs
depicted in FIGS. 1 to 8. The broken lines of even length
shown in the drawings illustrate portions of the door of the
compactor that form no part of the claimed design.**1 Claim, 8 Drawing Sheets**(56)
